LOUIS DÉSIRÉ JEANDRON-FERRY, OF PARIS, FRANCE.

Letters Patent No. 80,984, dated August 11, 1868.

IMPROVEMENT IN SHOES FOR BATHING AND OTHER PURPOSES.

The Schedule referred to in these Letters Patent and making part of the same.

TO ALL WHOM IT MAY CONCERN:

Be it known that I, LOUIS DÉSIRÉ JEANDRON-FERRY, of Paris, in the Empire of France, have invented a new and useful Improvement in Shoes for Bathing and other Purposes; and I do hereby declare that the following is a full, clear, and exact description of the same, reference being had to the accompanying drawings, forming a part of this specification, in which—

Figure 1 represents a side elevation of a bathing-shoe constructed according to my improvement.

Figure 2 represents an inverted view of the same, illustrating the construction of the sole.

Figure 3 represents a longitudinal vertical section of the same.

Figure 4 represents a similar view of a shoe, resembling that shown in figs. 1, 2, and 3 in all essential particulars, but having no heel.

Similar letters of reference indicate corresponding parts in the several figures.

The object of this invention is more especially to provide for the more effectual protection of the feet of bathers from the disagreeable effects of walking over a sandy beach after leaving the water, and also against injury from contact with stones, shells, and other sharp or angular substances while bathing, and at the same time to obtain a shoe more pleasant to wear than the shoes ordinarily worn by bathers; and to this end, it consists mainly in a novel construction of the sole, whereby the water is drained from the shoe by means of openings therein, but provision is made for the effectual exclusion of all solid substances.

To enable others skilled in the art to make and use my invention, I will proceed to describe it with reference to the drawings.

J is the upper part of the shoe, which may be composed of cloth or any other material not liable to injury by absorption of water.

K is the lacer or string with which the shoe is secured to the foot.

g is an inner sole, of cork or other suitable material, for protecting the foot from injury by the inequalities of the sole.

a is a sole, of leather, to which is secured the upper or cloth *J*.

e is a sole, of brass, securely riveted to the sole *a*, for the purpose of keeping the same in shape while it is in a saturated condition.

These three soles, *g*, *a*, and *e*, are pierced with openings, *b*, for the purpose of draining the water from the shoe when the operation of bathing is over.

The foot is protected from injury liable to be inflicted by the penetration of gravel and other sharp or angular substances up through the openings *b*, by means of a sheet of wire gauze inserted between the soles *g* and *a*, or *a* and *e*, whereby the passway through the openings *b* is effectually blockaded to said substances, but is sufficiently open, by means of the interstices of the wire gauze, to let out the water.

d is an outer strip of leather sole riveted to the brass sole *e*, to prevent the annoyance of slipping consequent to the contact of the brass sole *e* with the wet ground when the performance of swimming ceases, and pedestrian locomotion is resorted to; and also for the purpose of elevating the sole proper of the shoe slightly above the ground, so that the openings *b* may not come flat against the earth, in which case said openings would be closed by said contact, and the water remain in the shoe.

h is a metallic plate between the soles, and projecting forward from the heel far enough to strengthen the shank.

i is a metallic band surrounding the heel *e*.

What I claim as my invention, and desire to secure by Letters Patent, is—

1. A shoe, constructed with a perforated sole, through which, on the bather emerging from the water, egress is provided for the water from the interior of the shoe, substantially as herein described.

2. The metallic gauze, in combination with the perforated sole, substantially as and for the purpose herein specified.

JEANDRON-FERRY.
